Primary Examiner — John Windmuller(74) *Attorney, Agent, or Firm* — Aka Chan LLP(57) **CLAIM**

The ornamental design for an umbrella cap, as shown and described.

DESCRIPTION

This application is incorporated by reference along with U.S. patent application Ser. No. 29/461,658, filed Jul. 26, 2013.

FIG. 1 shows a perspective view of a design for an umbrella cap.

FIG. 2 shows a first side view of FIG. 1.

FIG. 3 shows a second side view of FIG. 1.

FIG. 4 shows a top view of FIG. 1; and,

FIG. 5 shows a perspective view of FIG. 1 in use in an umbrella.

The broken-line features in the figures are for illustrative purposes only and form no part of the claimed design. The umbrella in FIG. 5 is unclaimed environmental subject matter. The dot-dash lines represent boundaries of the claim.

1 Claim, 5 Drawing Sheets(56)
